UNITED STATES PATENT OFFICE.

JOSEPH S. WILLIAMS, OF RIVERTON, NEW JERSEY.

SUBAQUEOUS TUNNEL.

1,329,317.

Specification of Letters Patent. Patented Jan. 27, 1920.

Application filed December 8, 1906. Serial No. 346,892.

To all whom it may concern:

Be it known that I, JOSEPH S. WILLIAMS, a citizen of the United States, residing at Riverton, Burlington county, State of New Jersey, have invented a new and useful 5 Subaqueous Tunnel, of which the following is a specification.

My invention consists in its broad and generic scope of a novel subaqueous tunnel 10 in which a novel construction of tunnel sections is formed, such sections being established in a novel manner on a novel construction and arrangement of a foundation bed.

It further consists of a novel structure of 15 a tunnel and a novel construction of the foundation bed which is reinforced in such a manner that in case the entire foundation bed for a considerable length of the structure should be removed, the tunnel structure 20 will have the requisite tensile strength to carry the maximum loads without injury to the tunnel construction or the waterproofing thereof.

It further consists of a novel manner of 25 rendering waterproof a reinforced concrete tunnel construction.

It further consists of a novel manner of 30 uniting the tunnel construction with the shore terminals.

Numerous other objects of my invention will appear in the detailed description of 35 the invention.

For the purpose of illustrating my invention, I have shown herein embodiments 40 thereof which best illustrate the principles of my invention and which will give in practice satisfactory and reliable results, although it is to be understood that the various instrumentalities of which my invention 45 consists can be variously arranged and organized and that it is not limited to the precise arrangement and organization of these instrumentalities, as herein illustrated.

Figure 1 represents a longitudinal section 50 of a subaqueous tunnel construction embodying my invention and certain of its adjuncts.

Fig. 2 represents a plan view showing 55 the lines of survey for establishment of a subaqueous tunnel line.

Fig. 3 represents a side elevation partly in section of a portion of the tunnel.

Fig. 4 represents an end elevation partly

in section of a portion of a tunnel section 55 during one stage of the construction.

Fig. 5 represents a sectional plan view of a portion of the construction shown as partly completed.

Fig. 6 represents a perspective view 60 partly in section of a portion of a tunnel.

Fig. 7 represents a side elevation partly in section showing a portion of the tunnel line during its construction.

Fig. 8 represents a transverse section on 65 one of the section lines 6—6 of Fig. 7.

Fig. 9 represents a plan view of a portion of my construction.

Fig. 10 represents a plan view partly 70 broken away of an alining pier.

Fig. 11 represents a perspective view 75 partly in section of a portion of a double tunnel line.

Fig. 12 represents a perspective view 80 partly broken away of a multiple tunnelway construction showing certain details not seen in Fig. 11.

Fig. 13 represents in sectional elevation and partly in perspective a tunnel construction 85 as it appears when substantially completed.

Similar numerals of reference indicate 90 corresponding parts in the figures.

Referring to the drawings:—

1 designates the longitudinal central line 85 of a tunnel construction equidistant from which are two parallel lines 3 which define the exact width of the tunnel structure. 4 designates lines parallel with and exterior 90 of line 3 and at which pilings are driven, (see Fig. 10) upon which alining piers 5 are established (see also Fig. 7), said piers 5 being established on section lines 6. 7 designates platforms carried by the piling members and extending across the width of the 95 tunnel line and upon and across which a record is established to show clearly the lines on which the tunnel construction is to be established. The sections of the tunnel may have any desired length, but terminate 100 above one of the piers 5 as shown at 19 in Fig. 1.

9 and 10 designate adjustment lines upon which guide members 11 are established, such members being secured to the inner 105 sides of an alinement pier 85 to coöperate with guide members 12 of adjacent tunnel structures 13 and 14, in order to aline such

structures when they are placed in position on the pier grade line 15. 17 designate side guides having inclined parts for automatically guiding the tunnel sections into alignment between lines 3—3 upon which the inner faces of the side guiding members 18 are placed and maintained.

5 All records of the work to be done are established on the platform of the piers 5 10 so that visible records are formed showing the different operations to be carried out including the grade line 15 and the grade line 17 of the channel which is to be dredged.

15 The foundation bed is reinforced with any desired number of piers and at the ends of each tunnel section a pier is formed which is made of wood, cement or other piles, or caissons, which are reinforced with concrete, grouting or other material, thus forming a 20 fixed grade line, the upper face of which may consist of any desired reinforcements embedded in concrete to the exact grade line 15 and the piers which are at the ends of tunnel sections, I have designated as 2. The 25 foundation bed between the piers is reinforced by pilings 90 and ballast 91 to any desired standard. Any desired number of the piers may be provided with drainage wells 21 constructed in any desired manner 30 and in watertight union with the tunnel construction. 20 designates wharf structures at the shore ends of the tunnel and forming a continuation thereof and communicating with subway lines 144.

35

The tunnel sections.

40 The tunnel sections such as 13 and 14 may be constructed in the subwater line chambers of the wharf structures 20 or at any other desired location and are preferably formed as a floatable construction. Each tunnel section consists of a reinforced and water-proofed bridge framing consisting of girders which are provided with chords 22 and 23 45 having web plates 29 riveted or otherwise secured to angle members 30 so as to form a girder system as is best seen in Figs. 3, 4 and 5. 24 designates vertical I-beams secured to the upper chords 22 and the lower 50 chords 23 and also to truss members 25 which latter are secured to plates 26 secured to the I-beams 24. A structural metal truss girder extending in height from the bottom to the top of the construction is thus formed the 55 length of which corresponds to the length of a section. 27 designates transverse roof beams and 28 designates flooring or foundation beams secured to the members 30. 31 60 designates brackets secured to the longitudinal girder elements and the transverse roofing and flooring girder elements. 32 designates a bearing plate secured to the beams 28 and adapted to rest upon the head of a fixed grade line pier 2 or if desired a 65 plate 33 is attached to the base of the struc-

ture so as to present a bearing face for the end of the next tunnel section and a capping member 34 is also preferably provided at the upper end of a tunnel section. 35 designates side plates or jaws on opposite sides 70 of a tunnel section at its end, see Fig. 5, in order to form a chamber at the meeting ends of tunnel section to be filled with concrete. 36 designates foundation members of any desired material arranged longitudinally 75 and transversely and preferably with cutting edges at their bottom to provide for chambering the foundation area of the tunnel line and dividing the same into compartments to be subsequently filled with any 80 desired material. At each end of the tunnel section, the upright and transverse elements of the truss-frame structure are increased in number and are reinforced and secured together by means of brackets 31 and reinforcing plates 37 which latter are secured to angle pieces 38 to which end plates 39 are firmly secured to provide the necessary stability in such ends to enable bulk-heads 40, see Fig. 8, to be employed. 90

95 The side plates 35 have on their inner faces inclined slots 41 co-operating with lugs 42 on the sides of the tunnel section, see Fig. 7, so that the tunnel section on being lowered into position will be automatically drawn 95 into proper alignment with a tunnel section which has been placed. The end plates 39 of adjoining sections may be fastened together and the space between such plates, as seen in Fig. 5, is adapted to be filled by 100 forcing cement or grouting material through a conduit 43 and ports 44 in order to form a water-tight joint. After this is done a passage can be made through the bulk head 40 of one tunnel section and then through a 105 bulk head 40 of the adjoining tunnel section. 45 designates closures or valves for the conduits 43. 46 designates ballasting ports constructed in any desired manner and provided with removable water-tight valves 47. 48 110 designates a water-tight seal or plug in the outer end of the ballasting ports 46 adapted to be driven out from within the chamber of a tunnel section when it is desired to ballast therebeneath. 55 designates longitudinal 115 track stringers secured to the foundation element 28 and connected by fish plates or other members and embedded in concrete and water proofing material so as to operate as continuous members throughout the 120 length of the construction and across the union of meeting sections.

125 In order to properly secure together the ends of meeting tunnel sections lapping members 49 are built up, see Figs. 4, 6 and 11, so that a continuity of the chord and bridging construction is formed throughout it being understood that after the end plates 39 are riveted together, as at 50, and suitably calked the lining and lapping members 19 130

are placed in position, and lapping chord elements 97 and 98 are secured to the chord elements of the tunnel sections to form a continuity of the same throughout the tunnel line. The bridge framings above described are embedded in concrete preferably with a large percentage of cement or equivalent material therein and a layer of waterproofing 57 of any desired nature such as for example asphalt embeds the metal elements to a point near the ends of a section and the inside face of the plate 39, as shown at 59 at which point the waterproofing layer is of increased thickness. The waterproofing layer 57 is continued on the inner face of the sheathing member 58 which encompasses the reinforced concrete construction. This sheathing element 58 may be formed in any desired manner and in Fig. 6 consists of a plurality of layers of planks in which the inner layer 60 is covered by an outer layer 61 with a layer of waterproofing between the same and the element 58 is covered and enveloped by a layer of waterproofing 63. The layers of waterproofing 57, 62 and 63 are united at the ends of a tunnel section and are also united with an inner layer of waterproofing 64 and the layer of waterproofing between the layers 57 and 64 is designated as 65.

After lining the reinforced concrete construction with a layer of waterproofing 64 and closing the ports 89 in the bulk-heads 40, see Fig. 8, and establishing air lock chambers 66, see Fig. 7, the section will be about loaded sufficiently for floating into placement in the tunnel line. Any additional weight required may be formed by completing the construction to the inner line 70 or by filling a tunnel section with water or otherwise weighting the same. 75 designates an air shaft communicating with an air lock chamber 66. After a tunnel section has been connected with an adjoining tunnel section and the lap joint formed of the structural chords and other metal elements, the water proof layers are continued, as shown at 67, so that the lapping members 49 are faced with a layer of waterproof. The inner face of the lining member 49 is reinforced by a lining member 72 which may be provided with an inner lining member 73. A metal reinforcing element 201, as seen in Fig. 13, may be employed through which the layers of waterproofing become a unit between the outer boundary line 95 and the inner contour line 70 of the tunnel. I preferably increase the bridging capacity of a section by employing metal bars or chords 74, see Fig. 13, in which the space between 76 and 77 is provided with a filling of cement or concrete of reinforcing metal 78 embedded therein. Between 77 and 79 the waterproofing 202 is shown with reinforcing metal embedded therein together with cement or concrete. Between 79 and 80 the

waterproofing layer is shown faced with cement and vitrified brick 203. From 80 to 76 the waterproof is shown embedded in expanded, woven or perforated metal 81 embedded in concrete. 82 designates reinforcing bars extending across or encompassing the tunnel chambers. Chord members 83 and 84 are also seen in Fig. 13 united to the chords 22 and 23 respectively. The waterproof layers may be reinforced with metal 99, see Fig. 13. 200 designates longitudinal lines of waterproofing, see Figs. 11 and 13, which are in waterproof union with transverse lines of waterproofing 201 in order to localize any leakage. 203 designates reinforcing bars extending longitudinally through the construction and embedded in the concrete between the brackets 31 and the inner lining member and 204 designates similar bars employed at the upper end of the construction. These chords are united together to provide a continuity of chord elements throughout the tunnel and are anchored to the shore terminals and the chord elements 22 and 23 are also anchored to the shore terminals. The flooring is reinforced to longitudinally extending elements consisting of bars or metallic plates or beams to increase the bridging capacity of the construction.

Suitable means for supporting and guiding the tunnel section when lowering the same to placement are provided either on platform 7, floating vessels 93 or both and cables 92 are provided, see Fig. 8, and attached to the construction so that a tunnel section may be lowered to placement. Each tunnel section is provided with a cross bar 12 coöperating with the guide 11.

It will now be apparent that in carrying out my invention I reinforce the foundation bed after the same has been surveyed, by means of piers of any desired supporting capacity and the foundation bed between these piers is reinforced by piling and ballast to any desired capacity. The tunnel sections are then constructed to form a reinforced concrete tunnel section having a frame-work of structural metal embedded in concrete and layers of waterproofing. The ends of a tunnel section are then closed and such section is floated or otherwise transported into position above the prepared foundation bed so that when lowered the ends will be supported upon the piers. As a tunnel section is lowered to placement it interlocks with the end of a tunnel section already in place. The ends of the meeting sections are then embedded in waterproofing material and placed under air pressure after which the bulk-heads are broken down and the metal elements of the tunnel sections connected to form a continuity of structural metal construction which is then completed to the inner tunnel line 70 in the

manner described. Through the ballasting ports in the foundation part piles are passed and ballast so that the tunnel sections are ballasted into union with the foundation bed and form a unit of structure therewith. The tunnel sections at the shore ends are united with the subwater line chambers of the shore terminals 20 and are in waterproof union therewith. The drainage wells 21 are connected with the drainage wells 21 in the shore terminals 20. The piles supporting the working platforms 7 are then cut off or removed. I preferably establish side walls or pilings and fill in the channel with suitable material to the grade line, first driving pilings to a suitable standard of resistance and ballast or concrete the bed to alinement. Subsequently to the placement of the tunnel sections either of single or multiple tunnel construction, I ballast the reinforced concrete sections with concrete or other desired ballast and embed the sections at any desired portion, such as at the meeting ends, or along any part or the entire length of the tunnel line. Such side walls or pilings, as reinforcements in the tunnel bed, provide the desired resistance and reinforcement of the bed, and are especially designed to be employed where there is any uncertainty or shifting of the bed, and, if desired, continuously as a further reinforcement to the areas to the tunnel bed. The space between the side walls or parallel rows of pilings may be used for the piers or alining piers for the placing of the tunnel sections thereon in proper alinement. The sections thus placed may have the ends or the entire lengths between the piles or side walls filled with concrete which may be tamped and fill the space and cover the construction between the side walls. Any void that may remain in the bed under the tunnel may be filled with concrete through the ballasting ports in the tunnel construction. The ports may be afterward sealed, waterproofed, and capped to the line 70. By using a water sealing material to encompass the foundation area of the structure, the water may be pumped out of the ballast foundation compartment through pipes or flexible hose passed through the foundation ports 46, and the compartment, then practically free from water, can be filled with broken stone and grouting and a cement grouting may be employed upon the upper surface and as a filling for the ports.

When the tunnel sections are united in continuity and ballasted into union with the areas of the bed, it will be evident no break down or leakage can occur, especially when the construction is reinforced and protected by being embedded in concrete to cover the same with or without the side walls or pilings being employed and concreted into union therewith. In this manner the tunnel sections may be readily placed in position after being built in dry docks and made thoroughly water tight. The sections may be readily united in alined position and the water-proofing thereof protected by the concrete filling thereabove, whereby any number of sections may be placed in position on the bed and have a substantially water tight envelopment at the ends or throughout any desired length of the construction, so that any desired length of construction can be placed along the alined bed prior to making entrance into such construction for the completion of the meeting ends or the inner lining and equipment of the construction. 80

It will be apparent from the foregoing that the novel construction of tunnel herein disclosed may be very economically constructed since the same may be built in waterproof chambers of the shore terminals or on the land and then transported to placement and since the foundation bed is provided with a maximum of supporting and bridging capacity and the tunnel sections are formed of a reinforced bridge framing of truss metal work, any desired standards of load supporting capacity can be obtained. The construction is such that in case the foundation bed between piers is removed, the tunnel construction will have 95 the capacity of supporting maximum load. This invention provides for the building in and flotation from suitable sites, and the subsequent placement, alinement and anchorage, of large sectional lengths of single or multiple tunnelway monolithic construction along the excavated bed of a waterway, and for the chambering, embedment, anchorage and uniting of the juxtaposed ends of such sections from shore to shore; or throughout 100 any length of construction. It also provides for the ballasting and concreting of such construction into union with the bed, and the reinforcements and alining equipments of such bed, and for embedding the construction in concrete, whereby reliable standards of stability and capacities are provided which have not heretofore been obtained. 110

The inherent stability and capacities of 115 the construction prior to placement, serve to establish in the tunnelway encompassing walls a continuity of capacities to not only resist external pressures, but to form, when placed and concreted into union with the 120 bed and embedded to cover, a bridging support from the place of application of stress or strain, externally and internally, and vertically or laterally to abutment supports in continuity throughout the length of any 125 section, and otherwise throughout a series of sections and throughout the entire length of the tunnel.

The tunnel sections and otherwise the located tunnel construction, having a suitable 130

metal framing or trussed metal bridge framing, or trussed box girder bridge framing embedded in cementitious material, such as concrete, or asphaltum, or other suitable material, or a combination of such as herein described, will form and constitute a continuous metal framing reinforced monolithic construction, and otherwise a bridge framing or metal box girder reinforced cementitious tunnel.

Any one or all of such reinforcements embedded in cementitious material form and constitute a tunnelway or multiple tunnelways encompassing body, which will possess inherent qualities to provide for handling and transporting as floatable sections of construction when equipped with suitable bulkheads at the ends of the sections, and which will possess inherent qualities when sunk into alinement on suitable abutments or supports along an excavated channel bed, and concreted and anchored into union therewith, so that a continuity of coöperative tension, compression, trussing, anchorage and abutment supporting capacities are secured, whereby stresses, strains and vibrations, applied vertically or laterally, will be distributed and equalized from the place of application on any section of length by bridging actions continuously to continuous abutment supports in the capacities of the body and the bed, side walls and bed equipments with practical uniformity, and the strain will be distributed through the body to the bed and surrounding support, irrespective of the position of the load, relatively to the length of the construction.

The metal reinforcements in the tunnelway encompassing body of cementitious construction, are in tunnelway encompassing relationship with tension bridging capacities, crosswise and vertically, and otherwise sectionally in continuity in tunnelway encompassing relationship throughout the width and height, in combination with continuous tension and compression members extending therewith throughout the length of such construction, with any desired extent of trussing longitudinally, and in such relationship in such construction as to provide a continuity of tension, compression, trussing, anchorage and abutment support, vertically and laterally, from the place of application of stresses and strains, in continuity throughout the length of any section and series of sections, irrespective of the location of such stresses and strains, relatively to length of the construction.

In all the embodiments shown, the tunnelway encompassing body of metal reinforced cementitious construction, when concreted in union with the bed, will serve to function as a single or multiple tunnelway hollow bridge spanning girder or construction between abutment supports, and also a hollow

cantilever bridging construction on both sides of an abutment support, whereby the construction secures the advantages of both systems in practical continuity throughout any desired length of construction.

The anchorage and abutment supporting capacities are continuous throughout the length and in encompassing relationship to the metal reinforced cementitious tunnelway encompassing body forming continuous abutments therewith, whereby the abutment and anchorage capacities of the construction may be said to be continuous, on both sides of abutment support, and between abutment supports, for the determined bridging unit length and beyond such lengths in continuity, between the ends of section lengths, and otherwise throughout any desired number of sections of construction, or throughout an entire tunnel construction.

Such metal reinforced cementitious construction forms a reliable and stable base, for waterproofing, such as asphaltum, or pitch, or compounds of other material with such, with or without a wood or plate metal sheathing, or with a combination of such elements in the unit of such construction.

In all the embodiments herein metal reinforcements or framings provide bridging tension capacities in the base throughout the width of the body of construction and longitudinally thereof, along and into sides and in abutments of the roof or arch of the tunnelway encompassing cementitious body, and the reinforcing elements thereof, and in case of multiple tunnelways, tension reinforcements, or the metal bridge framings, include longitudinally metal tension members, or bridging girders, between tunnelways throughout the length, thereby reinforcing the roof and the base, with vertical supports therebetween, at such parts.

Such construction assures practical continuity of metal tension, compression and anchorage capacities in and across the horizontal and vertical planes, and in and about the tunnelway encompassing body of cementitious construction, throughout the length of any section, and otherwise, continuously throughout any desired number of section lengths of construction.

It will be evident sections of such reinforced construction with any desired length can be constructed under most favorable and economical conditions in suitable dry sites, or dry docks, or in any suitable location along the shores of the waterways, where provision can be made for flooding the site, and floating such construction therefrom to place, for sinking into tunnel alinement, along a suitable excavated, and alined, and reinforced channel bed of a waterway.

The work of channel excavation, bed reinforcement, and tunnel alining equipments, can be carried out expeditiously and eco-

nomically without risks attending various other systems of construction involving the use of pneumatic pressure.

The sections of construction, built in dry sites, or docks, will be subject to constant supervision, and the specified standards of construction, even to the waterproofing, can be insured and guaranteed, and when the construction is placed and concreted into union with the bed, and embedded in concrete, or other suitable filling, the tunnel will possess capacities not hitherto obtained in tunnel construction.

It will now be apparent that I have devised a novel and useful subaqueous tunnel which embodies the features of advantage enumerated in the statement of the invention and the foregoing description and while I have, in the present instance, illustrated and described the preferred embodiments thereof which in practice will give satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

30 1. A tunnel construction comprising sections of trussed metal bridge framing, capable of independent construction and movement, the said sections being united at their ends to transmit vertical and longitudinal strains through a plurality of sections, and cementitious material embedding the framing when in place.

40 2. A tunnel section, comprising a metal reinforced hollow monolithic girder having a trussed metal bridge framing embedded in its walls throughout a plurality of determined units of length, said section being capable of independent construction and movement and having a plurality of tunnel 45 passageways through it, each of said units of length being capable of supporting and distributing the strains of load and pressure to continuing unit lengths of the girder when placed.

50 3. A section of subaqueous tunnel construction, consisting of a reinforced concrete girder having its reinforcements embedded in concrete to form one or more tunnel passages, and preformed prior to placement on its bed, with the reinforcements, including tension members crossing all transverse sectional planes of said girder construction, and including reinforcing members supporting the tension members on and across trans- 60 verse sectional planes, whereby the section throughout its length and on all section lines has definite standards of load supporting and bridging capacity irrespective of the direction in which stresses and strains are 65 transmitted to it.

4. A section of subaqueous tunnel construction, consisting of a reinforced concrete girder having its reinforcements embedded in concrete to form one or more tunnel passages, and preformed prior to placement on 70 its bed, with the reinforcements, including tension members crossing all transverse sectional planes of said girder construction, and including reinforcing members supporting the tension members on and across trans- 75 verse sectional planes, whereby the section throughout its length and on all section lines has definite standards of load supporting and bridging capacity irrespective of the direction in which stresses and strains are 80 transmitted to it, and means to render the section floatable.

5. A subterranean tunnel construction comprising a plurality of sections consisting of reinforced concrete girders preformed prior to placement on their bed, and having their reinforcements embedded in concrete to form one or more passages, said reinforcements including tension members crossing all transverse sectional planes of 90 the construction, and including reinforcing members supporting the tension members on and across transverse sectional planes, whereby said girders have inherent in them definite standards for supporting stresses 95 and strains, on and across all section lines of construction, irrespective of the direction in which such stresses and strains are transmitted, and concrete embedding and uniting the ends of juxtaposed sections.

100 6. A subterranean tunnel construction comprising a plurality of sections consisting of reinforced concrete girders preformed prior to placement on their bed, and having their reinforcements embedded in concrete 105 to form one or more tunnel passages, said reinforcements including tension members crossing all transverse sectional planes of the construction, and including reinforcing members supporting the tension members on 110 and across transverse sectional planes, whereby said girders have inherent in them definite standards for supporting stresses and strains, on and across all section lines of construction, irrespective of the direction 115 in which such stresses and strains are transmitted, and concrete embedding and uniting the ends of juxtaposed sections, and a filling upon the bed to and against the base and side of said girders to form coöoperative 120 abutment supports therefor throughout the length and width of said girders, whereby said girders will be effectually anchored and protected and serve to stabilize and standardize the construction, and compensate for 125 variations in character of bed and provide a practical constancy of definite standards for supporting and distributing stresses and strains on any section in the length of the construction.

7. A reinforced concrete tunnel, comprising upper and lower chord members extending continuously throughout the length of the structure, vertical and lateral trussing connecting said chord members and surrounding the passageway, and concrete embedding said chord and trussing members

and forming the tunnel walls, whereby vertical load strains and lateral displacement strains will be resisted.

JOS. S. WILLIAMS.
